UNITED STATES PATENT OFFICE.

FARRELL C. HOCH AND WILLIAM I. MCKEE, OF BUTLER, PENNSYLVANIA.

OIL-WELL CLEANER AND AGITATOR.

1,086,050.

Specification of Letters Patent. Patented Feb. 3, 1914.

Application filed February 14, 1913. Serial No. 748,378.

To all whom it may concern:

Be it known that we, FARRELL C. HOCH and WILLIAM I. MCKEE, citizens of the United States, and residents of Butler, in the county of Butler and State of Pennsylvania, have invented certain new and useful Improvements in Oil-Well Cleaners and Agitators, of which the following is a specification.

10 The object of this invention is to provide a simple and efficient device for spraying the walls of an oil well for the purpose of dissolving paraffin and other accumulations which collect or become deposited in the oil bearing seams and stop or retard the flow of oil, decrease in the production of many oil wells being due to this kind of obstruction. Various forms of spraying apparatus have been proposed, but those which have been 20 most successful are more or less complicated and expensive to maintain and operate. These objections are overcome in the apparatus herein proposed which is of simple construction and is adapted to project 25 the cleaning or dissolving liquid with such force as to cause it to reach all portions of the obstructed wall surface.

A further characteristic of the invention is the facility and effectiveness with which 30 the device may be used for agitating the fluid in the well for loosening the seam obstruction and accelerating the flow.

In the accompanying drawings, Figure 1 is a vertical section of a portion of the length 35 of the improved cleaner and agitator, the position of the parts being as when the device is being lowered in a well, and Fig. 2 is a similar view with the device in lowered position and with the outlet valve opened by 40 contact with the bottom of the well, also with the piston in lowered position for ejecting the liquid. Fig. 3 is a top plan of the tool body, and Fig. 4 is a sectional plan on line 4-4 of Fig. 1.

45 Referring to the drawings, the main portion of the tubular body consists of a piece of commercial tubing 2 of suitable diameter, and secured to its lower end and forming a downward continuation thereof is the 50 tubular head 3, the latter having the threaded extension 3' which unites with the lower threaded extremity of tube 2, as shown. Head 3 is formed with a valve seat 4 and beneath the seat the walls of the head are 55 perforated at 5, the perforations being pref-

erably inclined upwardly from their inner ends.

6 is the downwardly seating valve carried by stem 7 which extends downwardly through stuffing box 7' in the lower portion 60 of head 3. Secured to stem 7 is the anchor-like extension 8 of any desired length, the lower extremity of the anchor being adapted to rest on the bottom of the well and hold the valve fixed while the valve seat lowers 65 therefrom and the body comes to rest on head 9, as in Fig. 2, with the valve in open position.

Movable vertically in the upper portion 70 of body 2 is the weighted piston 10 secured to stem 11 which extends through the upper end of the body and through a guide 12, the latter carried by stop-forming head 13 secured to the upper extremity of the body and of such size as to overhang the path of the 75 piston, being engaged by the latter, as in Fig. 1, for sustaining the weight of the tubular body when being lowered in or removed from a well. Piston 10 has a working fit in the body and is provided with 80 packing rings 10' to prevent excessive flow of liquid therearound when the piston is being operated. Body 2 may be provided with a filling hole 14 somewhat below the 85 uppermost position of the piston.

In operation, the tool is secured to a sand line or other cable or to rods for lowering in a well, the parts being in the position shown in Fig. 1, with the tubular body supported by piston 10. After the body has been filled 90 with benzin or other suitable cleaning or solvent liquid it is lowered in the well until anchor 8 reaches the bottom whereupon valve 6 is unseated, the body moving downwardly therefrom and coming to rest on 95 head 9, Fig. 2. The weighted piston is then permitted to move downwardly in the body, as in Fig. 2, forcibly ejecting the liquid through apertures 5 and spraying the walls of the well and dissolving or removing accumulations of paraffin and other matter that may be obstructing the flow of oil through the rock seams.

100 It is a common practice to "shoot" wells in order to increase the production, this being accomplished by dropping powerful explosive charges thereinto which results in laterally enlarging the bottom of the well, and apertures 5 of the cleaning device are inclined as shown to more effectively reach 110

the irregular surfaces of the shot-produced cavity than though the apertures were disposed horizontally. After the cleaning fluid has been discharged the device is removed 5 from the well by simply pulling upwardly on stem 11, the latter and the weighted piston supporting the body during its upward movement. The cleaning device may also be advantageously used for agitating the oil or 10 other fluid within the well—for instance the benzine after the latter has been discharged thereinto, this being accomplished by working the piston up and down in pump fashion while the body is supported on the well bottom. This results in alternately drawing 15 the fluid into the body and ejecting it therefrom, and this churning action is quite effective in opening the oil-bearing seams.

The apparatus is of simple construction, 20 the action of the valve is entirely automatic, and there are no projecting parts that are liable to be injured by contact with the well wall. The weighted piston 10 lowers with sufficient force to form the discharging liquid 25 into a strong and far-reaching spray.

We claim:—

1. The combination of a tubular body having a valve seat at its lower end and beneath the seat provided with lateral fluid outlets, 30 a downwardly seating valve, a stem depending from the valve through the lower end of the body, a piston movable in the body above the valve, and a piston operating stem.
2. The combination of a tubular body having a valve seat at its lower end and beneath the seat provided with lateral fluid outlets, a downwardly seating valve, a stem depending from the valve through the lower 35 end of the body, a piston movable in the body above the valve, a stop at the upper end of the valve engaged by the piston when the latter is in raised position, and a stem extending upwardly from the piston.
4. The combination of a body forming 40 tube, a tubular head secured to and forming

a downward continuation of said tube and formed with a valve seat, the head provided with lateral fluid outlets beneath the valve seat, a downwardly seating valve, a stem extending from the valve downwardly through the head, a piston movable vertically in the tube, and a piston operating stem. 50

4. The combination of a tubular body 55 formed with a valve seat near its lower end and with lateral fluid outlets beneath the valve seat, a valve for the seat, a stem depending from the valve through the lower end of the body, and an anchor extending downwardly from the stem and adapted to 60 support the body in lowered position with the valve unseated.

5. The combination of a tubular body 65 formed with a valve seat and with lateral fluid outlets beneath the seat, the outlets being inclined upwardly from their inner to their outer ends, a downwardly seating valve, a stem extending downwardly from the valve through the lower end of the body, a stuffing box in the body through which 70 the stem operates, an anchor extending downwardly from the rod and adapted to support the body in lowered position with the valve open, and a piston movable vertically in the body. 75

6. The combination of a tubular body formed with a valve seat near its lower end and with lateral fluid outlets beneath the valve seat, a downwardly seating valve, an anchor carrying stem depending from the 80 valve through the lower end of the body, a piston movable vertically in the body, a rod extending upwardly from the piston, and a stop at the upper end of the body and overhanging the path of the piston. 85

In testimony whereof we affix our signatures in presence of two witnesses.

FARRELL C. HOCH.
WILLIAM I. MCKEE.
